UNITED STATES PATENT OFFICE.

JOHN VAN BUREN, OF NEW YORK, N. Y., ASSIGNOR TO AMERICAN CHICLE COMPANY, OF NEW YORK, N. Y., A CORPORATION OF NEW JERSEY.

LABELING MACHINE.

Application filed September 23, 1920. Serial No. 412,348.

To all whom it may concern:

Be it known that I, JOHN VAN BUREN, a citizen of the United States, and a resident of the city of New York, county of Kings and State of New York, have invented certain new and useful Improvements in Labeling Machines, of which the following is a specification.

My present invention relates in general to sheet feeding apparatus and more particularly to machines for feeding and positioning sheets, and has special reference to the provision of an improved mechanism for feeding, reversing, and separating sheets.

While machines embodying my present improvements are adapted for a wide range of general usefulness in the art of handling sheets and the like, they find a field of special utility in serving the purpose of feeding sheets of labels, wrappers and the like and I shall accordingly proceed to describe my invention as embodied in a so-called labeling machine.

Obviously to work to advantage machines of the character referred to operate under conditions of relatively high speed, and must operate with precision. As the sheets of paper follow each other very rapidly through the machine, one of the great desiderata is to remove each sheet from the path of the following sheet in order to avoid interference between them, due to the tendency of the sheets to stick together by such adhesion as is incident to static electricity, suction or like phenomena.

Where it is attempted to accomplish such separation by mere differential drive or feeding action upon the several sheets, the difficulties involved have not been overcome.

The principal objects of my present invention, therefore, are the provision of a machine of the nature referred to characterized by such a feed of the stream of sheets that each sheet is positively separated from the sheet immediately following it, one wherein each sheet is diverted from the path of movement of the sheet next following, one wherein such separation is effected by imparting to each sheet a movement in a direction different from that of such following sheet, one wherein any interference be-

tween the successive sheets is avoided by accelerating the movement of the then leading sheet of the stream, one wherein rectification of the position of each sheet is accomplished immediately before it is discharged from the ultimate feeding element, one wherein the leading sheet is subjected generally to kinetic energy for the purpose of imparting accelerated movement thereto, and more particularly is so subjected when brought within the radius of action of the accelerated drive, one wherein generally the leading sheet is shifted bodily from one plane to another for avoidance of interference, and more particularly the rectification of position is effected during such shifting, one wherein the direction of movement of the leading sheet is generally reversed from that of the following sheet and particularly one wherein the adjacent sheets of the stream are both positively driven, one wherein such reversal is accomplished generally without imparting any strain upon the sheet and particularly by reversing the positions of the leading and following edges of the leading sheet, one wherein the kinetic energy utilized for positioning and accelerating the movement of the leading sheet is produced by retarding some portion of the leading sheet while another portion thereof continues to move and thereby the sheet is placed under compression, the provision generally of an improved mechanical movement for differentially driving the stream of sheets and more particularly one employing differentially speeded roller portions for such purpose, together with such further and additional objects as may hereinafter appear.

In attaining the objects referred to and gaining certain other benefits and advantages to be below pointed out, I have provided a construction, one embodiment whereof is illustrated in the accompanying drawings, wherein—

Figures 1 and 2 are elevational illustrations of lateral aspects of the machine, viewed from opposite sides, partly broken away in order to show certain details of construction;

Figure 3 is a vertical sectional view taken

on the line 3—3 of Figure 6, regarding the machine in the direction indicated by the arrows;

Figure 4 is a sectional view illustrative of 5 a part of the machine, similar to Figure 3;

Figure 5 is a horizontal sectional view taken on the line 5—5 of Figure 1;

Figure 6 is a plan view of the machine, looking at the machine in the direction indicated by the arrows 6—6 in Figure 1;

Figure 7 is a fragmentary view illustrative of a detail of construction.

As will be understood on reference to Figures 1, 2 and 3 of the drawings, in the present embodiment of my invention I provide a machine characterized by the provision of a suitable table, 10, for supporting a stack of label sheets indicated at A. The labels are held in position on the table, 10, by means of a reservoir, 11.

The labels are fed successively from the bottom of the stack by the intermittent contact therewith of the rotating separating member, 12, having frictional engaging portions, 13, positioned between the table edge, 15, and the end abutment member, 16, of the reservoir, 11.

For the purpose of assisting in the separation of the lowermost sheet from that immediately thereabove, the table, 10, is provided with a sharpened needle point or pin, 17, which pierces and engages the several lowermost sheets.

The holding action of the pin 17 is sufficient to overcome the tendency of the second lowermost sheet to adhere to and move with the lowermost sheet when the latter is advanced by one of the divided frictional surfaces, 13, until such second lowermost sheet is acted upon by the other divided frictional surface 13 of the member 12.

The friction between the surfaces 13 and the sheets with which they successively contact is sufficient to overcome the retarding effect of the pin 17.

The relative positions of the friction surfaces 13, are such that the sheets are advanced in overlapping relation.

As the successive sheets are advanced from the table, 10, by the member 12, they fall upon the lower feeding member or roller, 18, and are further advanced by the feeding members or rollers, 18 and 19, and are held in contact with the latter by the guide members 20.

These guide members, 20, are spaced across the width of the machine and are preferably in the form of wire members bent around the shaft, 21, of the roller, 18, at their lower end and at their upper end around the shaft 22 of the feed member or roller, 23, which also cooperates with the roller 19.

These guide members, 20, are so curved as to not only bridge the gap between the

rollers, 18 and 23, but also as to direct the oncoming sheet upwardly between the rollers 19 and 23.

As the sheet is advanced by the rollers 19 and 23 it rises to the position indicated by 75 dotted lines in Figure 3 and strikes the abutment 24 which acts as a retarder, as a guide and as a support for the upper end thereof.

The lower end of the sheet as it emerges 75 from between the rollers 19 and 23 rests momentarily upon the periphery of the roller 23.

This positioning is aided by the pressure of the adjacent end of the overlapping and 80 succeeding sheet of the stream, which tends to cause the lower end of the sheet indicated in the dotted lines to follow the periphery of the roller, 23, rather than that of the roller 19.

As the lower end of the sheet moves along with the periphery of the roller, 23, by the hooks 23^a, the sheet is raised bodily, the upper end thereof being guided in such movement by the guide 24.

The upper and lower ends of the sheet move in opposite directions due to the direction of rotation of the roller 23 and the direction of curvature of the guide 24, thus causing the sheet to shift both bodily and angularly until a point is reached where the sheet so canters that the upper end comes against the roughened abutment or stop members, 25, shortly to be described, and the lower end of the sheet immediately falls between the roller, 23, and the feeding member or roller 26.

The relation between the roller 23, guide 24 and members 25 is such that the position of the sheet is so rectified that the sheet is 105 then fed downwardly by said rollers 23 and 26 into the desired position for application to the article to which it is to be applied.

It is apparent that by the employment of two of the members 25 and the co-action 110 therewith of the roller 23, should the sheet emerge from the rollers 19 and 23 in an abnormal position such position will be rectified by one corner of the upper margin of the sheet engaging one of the members 25 115 which will restrain it from movement to permit the other corner to be lifted by the compression placed upon the sheet by the contact of the lower margin thereof with the roller 23.

In the actual operation of the machine a high speed is generally employed which causes the sheets to be rapidly ejected upwardly against the abutment or guide 24, moved bodily and angularly therewith or therefrom until it strikes one or both of the members 25, whereby its position is rectified and from which it rebounds downwardly at an accelerated speed due to the assistance of gravity. This rebound is further as 120 125 130

sisted and accelerated by the fact that the sheet is bent and straightens out as it strikes the members 25.

It will be readily discerned that a differential movement of the sheet in favor of its downward movement as compared with its upward movement is desirable in order that such downward movement may be accomplished by the leading sheet of the stream 10 without interference by the next following sheet and furthermore in order that there may be a short interval during which the leading sheet rests momentarily after emergence from the rolls 23 and 26 before it is 15 removed from the machine along with the article to which it is applied during such interval.

This differential movement is accomplished in part by means of the rebound of 20 the sheet as previously set forth and in part by means of the accelerated positive driving mechanism now to be described.

As will be seen on inspection of Figure 5, the roller 23 comprises three parts, 23^a, 25 23^b, and 23^c, mounted on the shaft, 22. The part 23^a is keyed to the shaft 22 to rotate therewith, and the parts 23^b and 23^c are loose on the shaft 22 and free to rotate independently thereof.

In order that the manner in which the two parts 23^a and 23^b of the roll 23 act differentially may be clearly understood, I will now proceed to describe the gearing by means of which the mechanism heretofore 35 set forth is driven.

Referring to Figures 2 and 6, it will be observed that power derived from any convenient source may be employed to rotate the main drive shaft, 27, carrying the roller, 40 12, and a gear, 28. The rollers 18 and 19 are driven from the gear 28 by means of gears 29, 30 and 31.

For rotating the part 23^c of the roller 23, a gear 32, which is keyed to the part 23^c, is 45 in mesh with the gear 31.

The shaft 33 which carries the roller, 19, has a gear, 34, at its opposite end. This gear 34 meshes with a gear 35 keyed to the roller portion 23^b.

By this arrangement the parts 23^b and 23^c of the roller 23 are driven at the same speed.

Now in order to drive the part 23^a of the roller 23 at a higher speed than the parts 55 23^b and 23^c thereof, the shaft 33 is provided with a larger gear, 36, meshing with the gear 37 which in turn meshes with the gear 38 fixed to the shaft 39 which carries the roller 26. There is keyed to the extension 60 40 of the roller 26 a gear 41 meshing with the gear, 42, fixed for rotation with the shaft 22 to which is keyed the part 23^a of the roller 23.

From the foregoing description of the 65 gearing, it will be manifest that the feeding

roller 26 and the part 23^a are driven at the same peripheral speed and the gearing is such that the speed of these two parts is greater than that of the parts 23^b and 23^c of the roller 23.

Furthermore, preferably the contour of the roller 26 is such that it cooperates only with the portion 23^a of the roller 23, and the portion 23^a of the roller 23 on the other hand is reduced at the points 43, 43 to prevent driving contact between such portion 23^a and the feeding members on the roller 19, which latter are however in driving contact with the roller 18 and certain of which are in driving contact with the parts 23^b and 23^c.

Reverting again to Figure 7, it will be seen that the abutment or guide member 24 is preferably a spring arranged between the stop members 25 and so disposed as to aid, 85 so far as possible, in the rectification of the sheet and accentuate the rebound thereof. The curvature of the abutment or guide 24 and the angle thereto of the abutment or stop members 25 are such as to serve the purposes above set forth most efficiently.

The abutment or stop members 25 may be conveniently carried on a supporting bracket, 44, variably supported by the frame member 45. These members 25 are preferably screw threaded through the bracket 44 for adjustment relatively thereto, which serves when desired a double function of permitting longitudinal variation of the stop members 25 relatively to the bracket, 44, and of enabling the presentation of a fresh roughened surface.

The variable support of the bracket, 44, is obviously such as to permit not only the angle of the members 25 relatively to the other elements to be varied, but also to permit a simultaneous lateral variation thereof.

It will be readily perceived on inspection of the drawings that the several parts of the machine, as a whole, are readily disassembled for repair, replacement and the like.

Having thus described my invention and illustrated its use, what I claim as new and desire to secure by Letters Patent is—

1. A machine of the character described comprising, in combination, means for feeding a stream of sheets in overlapped relation, and means for imparting accelerated movement to the leading sheet of the stream to prevent interference between the leading sheet and a following sheet.

2. A machine of the character described in which a sheet is to rest momentarily for a further operation, means for feeding a stream of sheets to the resting position, and means for imparting a further movement to the leading sheet of the stream at a higher rate of speed than that of said feeding means, whereby interference between the

- leading sheet and a following sheet is avoided while the leading sheet so rests momentarily.
3. A machine of the character referred to comprising, in combination, means for feeding a stream of sheets and means for imparting accelerated movement to the leading sheet of the stream, including differentially driven feeding means. 70
- 10 4. A machine of the character referred to comprising, in combination, means for feeding a stream of sheets and means for imparting accelerated movement to the leading sheet of the stream, including a feeder element having differentially driven portions. 75
- 15 5. A machine of the character referred to comprising, in combination, means for feeding a stream of sheets and means for imparting accelerated movement to the leading sheet of the stream, including feeding parts rotating differentially about a common axis. 80
- 20 6. A machine of the character referred to comprising, in combination, means for feeding a stream of sheets and means for imparting accelerated movement to the leading sheet of the stream, including a rotating feeding element having parts of its feeding surface differentially driven. 85
- 25 7. A machine of the character referred to comprising, in combination, means for feeding a stream of sheets and means for imparting accelerated movement to the leading sheet of the stream, including a plurality of differentially driven feeders having a feeding member forming part of more than one of said differentially driven feeders. 90
- 30 8. A machine of the character referred to comprising, in combination, means for feeding a stream of sheets and means for imparting accelerated movement to the leading sheet of the stream, including a divided feeding roller, certain parts of which are free for relative rotation. 95
- 35 9. A machine of the character referred to comprising, in combination, means for feeding a stream of sheets and means for imparting accelerated movement to the leading sheet of the stream, including a roller having driven end portions and an intermediate portion driven at a speed other than that of the end portions. 100
- 40 10. A machine of the character referred to, comprising, in combination, means for feeding a stream of sheets and means for imparting accelerated movement to the leading sheet of the stream, including a roller having driven end portions positively and simultaneously driven at the same speed and an intermediate portion driven at a speed other than that of the end portions. 110
- 45 11. A machine of the character referred to comprising, in combination, means for feeding a stream of sheets and means for imparting accelerated movement to the lead- 115
- 50 ing sheet of the stream, including a roller having driven end portions and an intermediate portion driven at a speed other than that of the end portions, and means for driving said end portions at the same speed. 120
- 55 12. A machine of the character referred to comprising in combination, means for feeding a stream of sheets and means for imparting accelerated movement to the leading sheet of the stream, including a roller having driven end portions, and an intermediate portion therebetween, and means for independently driving each of said end portions at the same speed, whereby a balanced drive feeding action by said end portions is effected. 125
- 60 13. A machine of the character referred to comprising, in combination, means for feeding a stream of sheets, and means for imparting accelerated movement to the leading sheet of the stream, including a roller having driven end portions, and a differentially driven intermediate portion therebetween, and means for independently driving each of said end portions at the same speed, whereby a balanced drive feeding action by said end portions is effected. 130
- 65 14. A machine of the character referred to comprising, in combination, means for feeding a stream of sheets and means for imparting accelerated movement to the leading sheet of the stream, including three co-acting rollers, two of which move at different speeds and the third has a plurality of portions, one of which portions moves with one of said first mentioned rollers and the other of which portions moves with the other of said first mentioned rollers. 135
- 70 15. In a feeding apparatus, a pair of feed rolls driven at different peripheral speeds and an intermediate roll having portions movable at the peripheral speeds of said pair of rolls. 140
- 75 16. In a feeding apparatus, a pair of feed rolls driven at different peripheral speeds, an intermediate roll having portions movable at the peripheral speeds of said pair of rolls, and means for passing an article between one of said pair of rolls and the intermediate roll in one direction and between the other pair of rolls and the intermediate roll in another direction. 145
- 80 17. In a feeding apparatus, a pair of feed rolls driven at different peripheral speeds, an intermediate roll having portions movable at the peripheral speeds of said pair of rolls, and means for passing an article between one of said pair of rolls and the intermediate roll in one direction at one rate of speed and between the other pair of rolls and the intermediate roll in another direction at a higher rate of speed. 150
- 85 18. In a feeding apparatus, a pair of feed rolls and an intermediate roll, means for passing a series of flat resilient articles be- 155

5 between one of said pair of rolls in one direction, a stationary abutment so positioned as to engage one edge of said articles to arrest the movement of said edge before the movement of the other edge thereof has stopped whereby said article is bent, said intermediate roll having projections arranged to engage and carry the edge of the article opposite the edge engaged by the abutment over toward the other of said pair of rolls and with said other of said pair of rolls to move the article in the opposite direction.

19. In a feeding apparatus, a pair of feed rolls and an intermediate roll, means for passing a series of flat resilient articles between one of said pair of rolls in one direction, a pair of spaced adjustable abutments arranged to engage one edge of said articles and arresting the movement of said edge before the movement of the other edge thereof has stopped whereby said article is bent, said intermediate roll being arranged to carry the edge of the article opposite the edge engaged by the abutments over to the other of said pair of rolls and with said other of said pair of rolls to move the article in the opposite direction.

20. In a feeding apparatus, a pair of feed rolls driven at different peripheral speeds and an intermediate roll having portions movable at the peripheral speeds of said pair of rolls, means for passing a series of flat, resilient articles between one of said pair of rolls in overlapped relation in one direction, an abutment arranged to engage one edge of said articles and arresting the movement of said edge before the movement of the other edge has stopped whereby said article is bent, said intermediate roll being arranged to carry the edge of the article opposite the edge engaged by the abutment over to the other of said pair of rolls and with said other of said pair of rolls to move the article in the opposite direction at a higher rate of speed whereby said articles are separated.

21. A machine of the character described comprising, in combination, means for feeding a stream of sheets in overlapping relation, and means for deflecting the leading sheet out of said stream and for moving it out of its deflected position at a higher rate of speed to separate said sheets.

22. A machine of the character described comprising, in combination, sheet feeding mechanism having means for changing the direction of the movement of the sheet including a curved guide and spaced abutment members angularly disposed in relation to said guide, and means cooperating with the guide for feeding the sheet against said members.

23. A machine of the character described comprising, in combination, means for

variably feeding sheets, including low speed feeding means and high speed feeding means for accelerating the movement of the leading sheet, and means between the two feeding means to cause the sheet to spring from one direction of movement imparted by one feeding means to the other thereof.

24. A machine of the character described comprising, in combination, means for variably feeding sheets longitudinally, including low speed upward feeding means and high speed downward feeding means.

25. A machine of the character described comprising, in combination, means for variably feeding sheets, including low speed upward feeding means and high speed downward feeding means, and means between the two feeding means for causing the sheet to spring from the direction of movement imparted by one feeding means to the other thereof.

26. A machine of the character described comprising, in combination, a sheet feeding mechanism, and means for rectifying the leading edge of the sheet, and means for manually adjusting the position of said rectifying means.

27. A machine of the character described comprising, in combination, a sheet feeding mechanism, means for rectifying the leading edge of the sheet, and means for adjusting the angular position of said rectifying means.

28. A machine of the character described comprising, in combination, a sheet feeding mechanism, means for rectifying the leading edge of the sheet, and means for adjusting the lateral position of said rectifying means.

29. A machine of the character described comprising, in combination, a sheet feeding mechanism, means for rectifying the leading edge of the sheet, and means for adjusting both the angular position and the lateral position of said rectifying means.

30. In the art of feeding sheets, the method of guiding a sheet to a feeding means comprising the forcible ejection of a sheet against a rectifying element whereby it is bent momentarily and caused to rebound into a position to be fed.

31. In the art of feeding sheets, the method of causing the sheet to change its course of movement and to be accelerated, including the step of ejecting the sheet against an abutment to bend the sheet first and then to cause the sheet to straighten in the opposite direction with an accelerated movement.

32. In the art of feeding sheets, the method of feeding a stream of sheets from a pile in one general direction in overlapped relation at one rate of speed, changing the direction of the stream of sheets and feeding the sheets in the new direction at a

higher rate of speed to separate the sheets.

33. In a feeding apparatus a pair of feed rolls and an intermediate roll, means for passing a series of flat resilient articles between one of said pair of rolls in one direction, a stationary abutment so positioned as to engage one edge of said articles to arrest the movement of said edge before the movement of the other edge thereof has stopped whereby said article is bent, said intermediate roll having a surface arranged to engage and carry the edge of the article

opposite the edge engaged by the abutment over toward the other of said pair of rolls and with said other of said pair of rolls to move the article in the opposite direction. In testimony whereof I have hereunto signed my name in the presence of the two subscribed witnesses.

JOHN VAN BUREN.
